T. A. CREIGHTON

RELEASABLE DRILL COLLAR

Filed Nov. 23, 1925

Patented Mar. 22, 1927.

UNITED STATES PATENT OFFICE.

THOMAS A. CREIGHTON, OF LONG BEACH, CALIFORNIA.

RELEASEABLE DRILL COLLAR.

Application filed November 23, 1925. Serial No. 70,868.

An object of my invention is to provide a drill collar which may be readily released from the bit when said bit becomes fastened in the well, so that the drill tubing may be removed from the well.

Another object is to provide a drill collar which may be released from the bit when said bit becomes fastened in the well so that the drill tubing may be rotated independent of the bit and said tubing may also be moved longitudinally a short distance.

A further object is to provide a drill collar which may be released from the drilling position on the bit, and which may then impart a jar to the bit to release said bit if it is fastened in the well, and may again be returned to the drilling position, on resuming cutting.

Other objects advantages and features of my invention may appear from the accompanying drawing the subjoined detailed description and appended claims.

In the drawing illustrating my invention—

Fig. 1 is a fragmentary longitudinal sectional view of my drill collar in the drilling position.

Fig. 2 is a fragmentary sectional view of my drill collar in released position.

Fig. 3 is a side view of the release nut.

Fig. 4 is an enlarged fragmentary sectional view of a form of locking pin for the safety collar.

Referring more particularly to the drawing my drill collar 1 consists of a tubular housing 2, to the upper end of which a hollow pin 3 is securely fastened. This pin is preferably screwed into the housing 2 and then welded in place. The lower section of the drill tubing 4 screws on to the pin 3, with a tight friction joint.

A safety collar 5 screws into the lower end of the housing 2, forming therewith the tight joint 6.

The collar 5 is internally threaded adjacent its lower end with a steep pitch right hand thread 7, and a hollow pin 8 is formed with threads 9 which screw into the collar 5. The purpose of these threads will be further described.

The lower end of the pin 8 is formed with a box 10 into which the bit 11 is adapted to tightly screw.

A release nut 12 is internally threaded with a left hand thread 13, and the pin 8 is formed with threads 14 adjacent its up-

per end which screw therein. The upper end 15 of the pin projects through and above the nut 12. The nut is of less diameter than the housing 2 and is free to move 60 therein. A cup washer 16 is secured to the upper surface of the nut 12 by a retainer 17, said washer preventing the passage of dirt, water, etc., between the nut and housing 2, which dirt may obstruct the free 65 movement of the nut.

As shown in Fig. 1 the drill collar is in cutting position and right hand rotation of the tubing 4 will cause the bit 11 to rotate and cut. It may be desirable to prevent 70 this right hand rotation from too tightly screwing the threads 9 into the collar 5. For this purpose I may employ a spring actuated locking dog 18 which is mounted in a recess 19 in the box 10. The upper face 75 20 of the dog 18 is cut aslant and fits into a notch 21 in the lower surface of the collar 5. Thus when the dog 18 falls into the notch 21 further rotation of the collar relative to the box 10 is prevented and the 80 threads 9 will not bind. Due to the slope of the upper face of the dog the collar 5 may be freely unscrewed.

Now if the bit 11 becomes fastened in the hole, and can not be moved left hand rotation of the tubing 4 will unscrew the collar 5 from the threads 9. Due to the steep pitch of the threads 9, they will not readily bind and will unscrew before any of the other joints in the tubing 4 or drill collar 1. 90 The pin 8 is made such a length that a considerable amount of longitudinal movement of the tubing 4 is possible before the upper surface of the collar 5 strikes the nut 12. The sudden striking of the collar against 95 the nut imparts a shock to the pin 8 and bit 11 which may serve to jar the bit loose. However if this is not successful the tubing 4 may be released from the bit as follows:

Lugs 22 depend from the nut 12 and are 100 adapted to fit into notches 23 in the upper face of the collar 5, thus coupling the nut to the collar and to the tubing 4. Right hand rotation will now unscrew the left hand threads 14 and thus release the tubing, housing 2 and collar 5 from the pin 8 and bit 11. A separate tool may now be employed to release and recover bit and pin.

Having described my invention I claim—

1. A drill collar comprising a housing, an 110 elongated pin, a bit adapted to be secured to the pin, releasable means connecting said

pin and said housing, a nut on said pin, said housing being adapted for longitudinal movement along said pin when said releasable means is released and means coupling said nut and said housing whereby said nut be removed from said pin to release said housing from the pin.

2. A drill collar comprising a housing, a pin extending into said housing, steep pitch threads on said pin screwing into said housing, a bit adapted to be secured to said pin, said threads being adapted to release said pin from the housing, a nut on said pin, said housing being adapted to engage said nut to limit the longitudinal movement of said housing on the pin, and means coupling said housing and said nut whereby said nut may be released from the pin.

3. A drill collar comprising a housing, an elongated pin, releasable means coupling said pin to said housing, a nut threaded on to said pin, and means coupling said nut and said housing whereby said nut may be

unscrewed when said releasable means is released.

4. A drill collar comprising a housing, an elongated pin, a nut threaded onto said pin, releasable means coupling said pin to said nut and said housing whereby said nut may be unscrewed when said releasable means is released, said coupling means comprising lugs depending from said nut, and said housing having recesses therein adapted to receive said lugs.

5. A drill collar comprising a housing, an elongated pin, releasable means coupling said pin and housing, a nut threaded onto said pin, lugs depending from said nut, said housing having recesses therein, adapted to engage said lugs to unscrew the nut when said releasable means is released, and a cup washer on top of said nut.

In testimony whereof I hereto affix my signature.

THOMAS A. CREIGHTON.
